UNITED STATES PATENT OFFICE.

LOUIS M. HOFTRUP, OF ELMIRA, NEW YORK.

DRAFT FOR TRACTOR-PLOWS.

1,386,836.

Specification of Letters Patent. Patented Aug. 2, 1921.

Application filed December 16, 1920. Serial No. 431,211.

To all whom it may concern:

Be it known that I, LOUIS M. HOFTRUP, a citizen of the United States of America, residing at Elmira, in the county of Chemung and State of New York, have invented 5 certain new and useful Improvements in Drafts for Tractor-Plows, of which the following is a specification.

The primary object of the invention is the 10 provision of a draft connection especially designed for tractor plows although serviceable wherever a plurality of members are to be pulled forwardly, the structure providing flexibility and self-alinement of the 15 drawn members.

A further object of the invention is the provision of a draw point for tractor plows, permitting vertical and slight lateral adjustment of the plows during travel where- 20 by two plows may be employed as a two-way plow for side-hill work.

A still further object of the invention is the provision of a flexible self-aligning draw point for two plows resulting in the automatic 25 positioning of the plow in condition for work upon the land over which the device travels regardless of the contour of the land such as the sloping position thereof.

With these general objects in view the invention consists in the novel combination and arrangement of parts hereinafter more fully described in connection with the accompanying drawing and in which like reference characters designate corresponding 35 parts throughout the several views.

In the drawing:—

Figure 1 is an elevational view of a plow beam provided with my invention a portion of the beam and plow being illustrated by 40 dotted lines,

Fig. 2 is a top plan view thereof,

Fig. 3 is a horizontal sectional view of the same and

Fig. 4 is a vertical transverse sectional 45 view taken upon line IV—IV of Fig. 1.

Referring more in detail to the drawing, my invention broadly consists of draft connection 10 resiliently and pivotally carried between the forward extensions 11 of plow 50 beams 12 whereby two plows 13 such as indicated by dotted lines in Fig. 1 of the drawing are forwardly propelled by connecting up the draft connection 10 with suitable traction means such as a tractor, 55 not shown. A dished disk 13 is secured to

the inner face of each extension 11 by bolts or similar hold-fast devices 14 with ribs 15 upon the outer faces of the disks 13 directly engaging the inner faces of the extensions 11 thereby slightly spacing the disks 13 60 therefrom.

The draft connection 10 includes an annular or wheel-shaped body 16 adapted for receiving the disks 13 within the opposite sides thereof in contact with the circular central 65 web 17 of said body 16, with the annular edges 18 of the disks 13 engaging the opposite faces of the web 17 and with the heads 19 of the bolts 14 accommodated within the inner dished sides of the disks 13 and spaced 70 from the web 17.

A journaling shaft 20, here illustrated in the form of a bolt projects through a central perforation 21 of the web 17, central perforations 22 of the disks 13 and through 75 corresponding perforations 23 in the extensions 11. Coil springs 24 surround the shaft 20 outwardly of the extensions 11 being seated upon the washers 25 carried by the shaft 20 in contact with the extensions 11 80 and similar washers 26 upon the shaft 20 adjacent the opposite outer ends of the shaft, which ends are provided with a head 27 and a threaded nut 28 respectively.

An attaching plate 29 is carried by the 85 body 16 with a plurality of perforations 30 for the attachment of clevises, chains or other suitable means, not shown, for attaching the same to a tractor or other power device.

The complete operation of the invention will be fully understood from this detailed description thereof, the draft connection 10 being hauled forwardly drags the plows having the plow beams 12 and permits relative vertical shifting of the plows during forward travel. Slight lateral adjustment is also permitted, the springs 24 serving to automatically return the beams 12 to their normal parallel positions. The connecting 95 device is in this manner rendered flexible and connects the plow beams for self-alinement during operation, the upward and downward movements of the plow having no effect upon the firm attachment for draft 100 purposes between the plow beams 12 and the draft connection 10.

A serviceable device is provided and while the form of the invention herein set forth is believed preferable, it will be understood 110

that minor changes may be made therein without departing from the spirit and scope of the invention as claimed.

What I claim as new and desire to secure 5 by Letters Patent is:—

1. A draft device for plow beams comprising disks adapted for rigid attachment to the beams, a connecting member having a circular body within which the disks are 10 normally positioned and resilient journaling connections between said disks and body.
2. A draft device for plow beams comprising disks rigidly secured to the inner faces of the beams, a wheel-shaped body 15 with the disks normally seated within the opposite sides thereof and journaling connections between said disks and body.
3. A draft device for plow beams comprising disks rigidly secured to the inner 20 faces of the beams, a wheel-shaped body with the disks normally seated within the opposite sides thereof, journaling connections between said disks and body, a journaling shaft centrally projecting through 25 said disks and body and resilient means adjacent the outer ends of the shaft adapted for permitting slight lateral play between the beams during operation.
4. In combination with plow beams, forward 30 extensions carried thereby, dished disks rigidly secured to said extensions slightly spaced inwardly thereof, a wheel-shaped body having a central web and adapted for overlying said disks when the 35 device is assembled, and a journaling shaft axially positioned through said web and disks and projecting through said extensions.
5. In combination with plow beams, forward 40 extensions carried thereby, dished disks rigidly secured to said extensions slightly spaced inwardly thereof, a wheel-

shaped body having a central web and adapted for overlying said disks when the device is assembled, a journaling shaft 45 axially positioned through said web and disks and projecting through said extensions, springs encircling the opposite end portions of the shaft tensioned between said extensions and the end portions of the shaft 50 and an attaching plate carried by said body.

6. A device of the class described comprising plow beams, forward extensions carried thereby, dished disks having rib portions upon their outer faces engaging the 55 inner faces of the extensions, bolts secured through said disks and extensions with the inner end portions of the bolts within the inner dished portions of the disks, a wheel-shaped connecting body surrounding said 60 disks with a central web in normal contact with the inner edges of the disks and journaling connections between the extensions and body.

7. A device of the class described comprising plow beams, forward extensions carried thereby, dished disks having rib portions upon their outer faces engaging the inner faces of the extensions, bolts secured through said disks and extensions with the 70 inner end portions of the bolts within the inner dished portions of the disks, a wheel-shaped connecting body surrounding said disks with a central web in normal contact with the inner edges of the disks, the disks 75 and web having central perforations and the extensions having perforations in alinement therewith when the device is assembled, a journaling shaft through said perforations and resilient members engaging between the 80 outer faces of the extensions and the opposite end portions of the shaft.

In testimony whereof I affix my signature.
LOUIS M. HOFTRUP.
